Specification for Design.

Patented Mar. 18, 1913.

Application filed January 2, 1913. Serial No. 739,894. Term of patent 3½ years.

To all whom it may concern:

Be it known that I, ROBERT CASARETTO, a subject of the King of Prussia, and a resident of the city of Crefeld, Germany, and whose post-office address is 7 Alexanderplatz, have invented a new and original and ornamental Design for Textile Fabrics, of which the following is a specification, reference being had to the accompanying drawing, forming part thereof.

The figure is a plan view of a portion of the textile fabric, showing my new design.

I claim:

An ornamental design for a textile fabric, as shown.

Signed at the city of Aix-la-Chapelle, Germany, this 6th day of December 1912.

ROBERT CASARETTO.
